Des. 171,320

BUG AND AIR DEFLECTOR FOR AUTOMOBILES

Filed April 20, 1953

UNITED STATES PATENT OFFICE

171,320

BUG AND AIR DEFLECTOR FOR AUTOMOBILES

Forrest Berry, Reading, Pa.

Application April 20, 1953, Serial No. 24,587

Term of patent 7 years

(CL. D14—6)

To all whom it may concern:

Be it known that I, Forrest Berry, a citizen of the United States, residing at Reading, in the county of Berks and State of Pennsylvania, have invented a new, original, and ornamental Design for a Bug and Air Deflector for Automobiles, of which the following is a specification, reference being had to the accompanying drawing, forming a part thereof.

Fig. 1 is a front perspective view of a bug and air deflector for automobiles showing my new design;

Fig. 2 is a front elevational view;
Fig. 3 is a top plan view; and

Fig. 4 is an end elevational view.

I claim:

The ornamental design for a bug and air deflector for automobiles, as shown.

FORREST BERRY.
